COUPLING DEVICE

John F. Kopczynski, Buffalo, N. Y.

Application May 1, 1943, Serial No. 485,355

12 Claims. (Cl. 164—124)

This invention relates to coupling devices and especially to those which are utilized for coupling a tool to a holder therefor.

An example of such a tool and holder is a punch element and a holder therefor which are commonly employed for punching apertures in blanks. In such devices the punches frequently break in use, and it is highly desirable to provide for quick detachment of the broken punch and its replacement by a fresh punch. It becomes necessary at intervals during use to grind the worn free ends of the punches in order to renew them and where a plurality of punches are mounted on the said holder, it is desirable that this grinding of the ends of the punches be done as a group in a simple and rapid manner.

An object of this invention is to provide an improved coupling between a stud and a holder therefor by which the post may be easily and quickly attached to or removed from the holder by simple manipulative movements; with which the post may be securely held within the holder during use, and which will be relatively simple, effective, compact and inexpensive.

Another object of the invention is to provide an improved coupling between a tool element and a holder therefor, by which the tool element may be attached to or removed from the holder by simple rotary and endwise movements of the tool element relatively to the holder, yet with the tool element held securely in the holder during use, the device being produced by simple and inexpensive methods of manufacture.

Another object of the invention is to provide an improved holder with which tools or other elements may be releasably coupled thereto and uncoupled therefrom by simple movements; and which may be made at lower cost than prior devices for accomplishing the same result.

Another object of the invention is to provide an improved punch device of the type having a stripper carried by the holder and with which the punches may be coupled and uncoupled from the holder by simple manipulative movements; with which the stripper may be separated into parts in a simple manner to permit the application of an appliance to a punch to insert it in or remove it from the holder; and which will be relatively simple and inexpensive.

Another object of the invention is to provide an improved coupling between a tool and a holder, with which the tool element will be held properly positioned and held against unintentional rotary displacement while being assembled

in operative relation to a stripper, and which will be relatively simple and inexpensive.

Other objects and advantages will be apparent from the following description of some embodiments of the invention, and the novel features will be particularly pointed out hereinafter in connection with the appended claims.

In the accompanying drawings:

Fig. 1 is a sectional plan of a holder constructed in accordance with this invention, the portion of one corner being broken away to show other details;

Fig. 2 is a sectional elevation of a part of a punch press having the holder, stripper and punch constructed in accordance with this invention, the section corresponding to one taken along the line 2—2, Fig. 1;

Fig. 3 is a sectional plan through a portion of the same, the section being taken approximately along the line 3—3 of Fig. 2, between the faces of two of the abutting plates, forming the holder.

Fig. 4 is a sectional plan of a portion of the same, the section being taken approximately along the line 4—4 of Fig. 2;

Fig. 5 is a perspective of a wrench or appliance that may be used to apply the punches to or remove them from the holder;

Fig. 6 is a sectional elevation through a portion of the holder to show coupling means between the sections of the stripper, the section being taken approximately along the line 6—6 of Fig. 1.

Fig. 7 is a sectional plan of a modification of the construction shown in Fig. 6;

Fig. 8 is a sectional elevation of the same, the section being taken approximately along the line 8—8 of Fig. 7; and

Fig. 9 is a sectional plan similar to Fig. 3 and illustrating a modification thereof.

Referring first to Figs. 1 to 6, the invention is shown as applied to a punch press of simple form in which the piercing punch 1 (Fig. 2) is releasably secured to a holder 2 which is carried by a shank 3 that is suitably supported on a movable press member. The holder 2 is formed of a plurality of flat metal plates 4, 5, 6 and 7, which are disposed face to face and flat against one another sequentially, and they are removably coupled together in any suitable manner, or they may be permanently coupled together after the device has been assembled. The plates 5, 6 and 7 are provided with aligned bores or apertures 8, 9 and 10 respectively, which pass from face to face and together constitute a recess R extending from the interior zone of the outside face of the plate 7.

at one end of the sequence. This recess R extends in a direction normal to the outside face of the plate 7. This recess is generally cylindrical in form and of a size to receive the cylindrical shank 11 of the piercing punch for rotation and endwise sliding movement when the punch is inserted endwise in the recess 10.

The hole 9 of the plate 6 which forms part of the recess R is slightly larger than the alined holes 8 and 10. The plate 6 is also provided with an aperture 12 from face to face, Fig. 3, which intersects the bore 9 slightly at one side thereof. It will be noted that the aperture 12 and bore 9 in plate 6, while intersecting one another, are entirely encircled by unapertured portions of the plate 6 and aperture 12 is also closed at both faces by the abutting plates 5 and 7 and is, in effect, a cavity in the holder. Disposed in the aperture 12 is a flat key 13 in the form of a plate which is guided in its ends by two opposite side walls of the aperture 12. The key 13 is of uniform thickness, slightly less than the thickness of the plate 6, so that this key 13 will slide freely in the aperture 12 in a direction radially toward and from the longitudinal axis of that portion of the recess formed by the bore 9.

The shank 11 of the punch 1 which is received within the recess R formed by the alined bores in plates 5, 6 and 7, is provided with a transverse kerf of slot 14 which extends transversely across the shank at one side thereof in alinement with the aperture 12. This kerf or slot has its side walls in flat parallel planes normal to the longitudinal axis of the shank 11 of the punch. The plane of the side wall 15 of the kerf 14 which first enters the recess in the holder will be substantially coincident with the planes of the abutting faces between the plates 5 and 6 when the shank 11 is fully within the bores 8, 9 and 10, as shown in Fig. 2, so that the key 13 may be moved into the kerf or slot 14 to latch the shank 11 within the holder. The width of the kerf or slot 14 is, of course slightly greater than the thickness of the adjacent edge wall zone of the key 13, so that the key 13 may move freely into and out of the kerf.

Within the cavity 12 of the plate 6 I provide a helical compression spring 16 which is disposed under compression between an edge wall of the aperture 12 and a corresponding parallel edge wall of the key 13. This spring yieldingly and continuously urges the key 13 into a position partially across the bore 9 and thus to a slight extent across the recess R formed by the alined bores 8, 9 and 10, but the engagement of the key with the edge wall of the aperture 12 adjacent the bore 9 will limit the extent to which the key may be projected across the recess in the holder.

To prevent accidental displacement of the spring 16, the edge wall of the cavity 12 against which an end of the spring 16 abuts is provided with a shallow notch or recess 17 to receive the adjacent end of the spring 16, and the key 13 is similarly provided in its edge wall engaged by the spring 16 with a notch 18 into which the end of the spring is received. The spring 16 is held in position and against displacement by the notches 17 and 18 and by the faces of the plates 5 and 7 which abut the plate 6. The free end of the shank 11 which is the end that first enters the recess formed in the plates 5, 6 and 7, is chamfered on an edge thereof, as at 19, preferably directly in endwise alinement with the kerf 14, so that when the shank 11 of the punch is inserted in an endwise direction on the bore 10

in plate 7, this chamfered end edge will engage with the key 13 and cam the latter aside as the shank is pushed endwise into recess R to enable continued movement of the shank 11 into and along the bores 9 and 8. As soon as the kerf 14 moves into alinement with the key 13, the latter will be snapped into the kerf to latch the shank 11 within the holder.

In use, the shank 11 of the punch 1 may tend to bind in the recess in the holder, and in such a case it may be necessary to apply a tool to the punch to rotate it so that the cylindrical, peripheral wall of the shank adjoining the kerf may cam key 13 back into the cavity 12 and out of the bore 9 until it releases the shank 11 of the punch. Then, when the punch 1 is moved endwise, it will be disengaged from the holder. For this purpose, the shank 11, in a zone outside of the recess in the holder, which will be below the plate 7 in Fig. 2, is provided with one or more transverse kerfs 20, and a tool or wrench, such as shown in Fig. 5, may then be applied to the shank at these kerfs to turn the punch and move it endwise. This tool 21 shown in Fig. 5 is provided with arms 22 having a distance or gap between them such that these arms may slide along the bottoms of two opposite kerfs 20 of the shank 11 of the punch. The side walls of these kerfs act as shoulders abutting endwise of the shank against the wrench, so that when the wrench 21 is turned or moved endwise, it will impart similar movements to the punch 1. This wrench 21 may have a handle portion 23 by which it may be turned and moved endwise.

With a punch of this type, the stripper plate may be mounted on a base having the tool with the aperture therein, or it may be mounted on the holder. In this particular example, the stripper is mounted on the holder. The stripper, designated generally by reference A, is formed of two flat plates 24 and 25 which abut face to face and are removably coupled together. Shouldered screws 26 are threaded into the plate 24 so as to extend therefrom towards the plates 4, 5, 6 and 7, and the shanks of these screws 26 extend through and slide endwise in apertures 27 in the plate 7, and into recesses 28, 29 and 30 in the plates 4, 5 and 6 respectively.

The heads 31 of the screws thus are slidably and rotatably disposed within the alined recesses 28, 29 and 30, but engagement of the heads 31 with the plate 7 will limit the movement of the plate 24 in a direction away from the holder 2 formed by the plates 4, 5, 6 and 7.

A helical compression spring 32 surrounds each screw 26 and is under compression between the plate 7 and the plate 24 so as to yieldingly urge the plate 24 in a direction away from the plate 7 to the extent permitted by the engagement of the heads 31 of the screws 26 with the plate 7. The plate 24 is provided with an aperture 33 entirely therethrough and alined with the punch 1. The aperture 33 is of a size to freely pass the wrench therethrough and to enable it to be applied to or removed from the shank 11 of the punch with the handle part of the wrench descending below the punch and the plate 24. The plate 25 of the stripper is provided with a passage 34 which slidably fits the piercing end of the punch 1 and into which passage the free end of the punch is withdrawn when the punch is retracted and withdrawn from the blank.

The blank is designated by the reference character B in Fig. 2, and it is supported upon the upper face of the die 35 having the die opening

36. The die opening 36 at its lower end is divergent as at 37, to form a blank channel through which the slugs punched from the shank B may be discharged. In the event of breakage of a punch, one merely uncouples the plate 25 from the plate 24 in the stripper A, and then removes the plate 25 which enables one to pass a wrench, such as shown in Fig. 5, upwardly through the aperture 33 in the plate 24. The wrench, after being applied to the punch, is first rotated through a part revolution to cause disengagement of key 43 from the kerf 44, and is then pulled endwise to remove the punch from the holder. A new punch may be inserted in the holder by a similar but reverse series of operations, and the plate 25 is then applied over the free end of the punch 1 and coupled to the plate 24.

Since the plate 24 is not removed, the springs 32 are not released and the replacement of a punch is a simple operation. Where a number of punches are carried by the same holder, and it is desirable to grind the free ends of the punches after extensive use, this can be done while the punches remain in the holder by merely removing the plate 25, which exposes the free ends of the punches, and then the free ends can all be ground off to the same extent by a single grinding operation and while the punches remain mounted in the holder. This effects a considerable saving in time by grinding the free ends of the punches as a group.

Any suitable means may be employed for coupling the plates 24 and 25 of the stripper A. A very satisfactory coupling is shown in the upper left hand corner of Fig. 1, and in Fig. 6. Referring particularly to Fig. 6, a shouldered element or stud 38 is secured, such as by riveting, to the plate 25, and its free end rotates and slides endwise in an aperture 39 in the plate 24 and also projects beyond the plate 24. This projecting portion of the stud 38 extends into a coupling member 40. This member 40 is formed of two plate-like sections *a* and *b* abutting face to face and having aligned apertures therethrough to form a recess 41 into or through which the stud 38 extends. One of these sections, such as the section *a*, is provided on the face abutting the section *b* with a cavity 42 which intersects the recess 41 slightly, but is otherwise entirely encircled by uncut portions of the member 40. Within this cavity 42, I mount a key 43 which slides in a linear direction and radially toward and from the axis of the recess 41, see Fig. 1 also, into and out of a transverse kerf or slot 44 provided in the side of the post or stud 38.

A spring 45 is disposed in the cavity between an edge wall of the cavity and an edge wall of the key so as to yieldingly urge the key 43 into a kerf or slot 44 in the stud 38 when the stud is within the member 40, as shown in Fig. 6. The spring 45 may be received in notches 46 in the edge walls of the key 43 and the edge wall of the recess 42, so that it cannot get out of operative position. The sections *a* and *b* of member 40 are spot-welded or otherwise coupled together face to face after the key 43 and spring 45 are inserted in the cavity, and the member 40 thus acts as a quick detachable nut on the stud 38 which can be released by a relative 90° movement between the member 40 and the stud 38. The free end of the stud 38 is chamfered along one edge, as at 47, Fig. 6, so that when the member 40 is applied over the end of the stud 38, the chamfered edge will cam the key 43 aside to

permit relative movement of the stud 38 fully into the member 40, and then the key 43 will be snapped into latching position in the kerf or slot 44 by the spring 45.

5 In Figs. 7 and 8, a slight modification of this type of coupling is shown, in which the member 48 is similar to the member 40, except that it has laterally extending ears 49 which may be secured to the plate 24, such as by rivets or screws 50. Similarly the stud 38 of Figs. 1 and 6 is replaced by a stud 51 which has a frusto-conical head 52 received in a tapered or countersunk seat in the plate 25. Stud 51 has a slot or recess 53 in its end face by which it may be turned through the use of a screwdriver or other tool to uncouple the member 48 and stud 51. The other parts of the coupling are the same as in Figs. 1 to 6 and are given corresponding reference characters.

With this modification, when one desires to uncouple the plate 25 from the plate 24, the holder with the stripper attached thereto is elevated or backed away from the die and blank, and then the stud 51 is turned through one-quarter revolution or more, during which the cylindrical surface of the stud 51 cams the key 43 aside in the cavity 42, whereupon the plate 25 may be pulled away from the plate 24 which removes the stud 51 from the members 48. To reapply the plate 25 to the plate 24, these plates are brought into face to face abutting engagement, and then the stud 51 is inserted endwise through the plate 25 into the plate 24 and into the cap member 48 which is permanently secured to the plate 24. The chamfered end edge of the stud 51 cams the key 43 aside, and then when the kerf or slot 44 moves into alignment with the key 43, the latter is snapped into latching engagement in the kerf. This arrangement therefore is quite similar to that of Figs. 1 to 6, except that the stud member 51 corresponding to the stud 38 of Figs. 1 and 6 is turned to uncouple the plates, instead of rotating the coupling member 40, as in Fig. 6.

In many instances, the free ends of the punches are non-circular and may even be square or rectangular so that they will punch non-circular or rectangular square holes in the blanks, and in such a case the apertures 34 in the stripper plate 25 are made of the same shape as the free ends of the punches so as to slidably fit the latter. While each punch is yieldingly held in proper angular or rotary position by the engagement of the related key 13 against the flat bottom wall of the kerf 14 in the shank 11, nevertheless some additional means may be desirable to insure that the punches are properly held to enter the passages in the plate 25, because if the shanks 11 of the punches turn hard in the holder recesses, one may not be able to tell when the key 13 engages fully along the entire flat bottom of the kerf 14.

In such a case, one may use the modification shown in Fig. 9, in which a kerf or slot 54 in the shank 11 is formed, as explained in Figs. 1 to 6, and also a second kerf 55 may be formed in the shank 11 at right angles to and at one end of the kerf 14, but the kerf 55 need not extend more than partly across the side of the shank 11. The key 13a is made L-shaped so that the angular end 55 may enter this second kerf 54. Then one may merely rotate the shank 11 in the direction of the arrow 56, Fig. 9, until the corner of the shank 11 between the two kerfs engages in the inside corner between the base and side of the L and against the angular end 55 of the key.

which provides a definite stop for locating the punch. To release a punch formed in this manner, the punch is merely rotated in the opposite directions, such as in the direction of the dash line arrow 57 of Fig. 9, in which case the inner end of the second kerf 54 engages against the end of the angular end 55 of the key and cams the key into retracted position, where it releases the shank 11.

The aperture 12 may be punched out at low cost, and because the metal of the plate may be distorted slightly, in the punching operation, around the aperture, the hole or bore 9 is made a little larger than the bores 8 and 10 so that it will not restrict the diameter 8 of the recess R. Actually the bore 9 and the aperture 12 may be formed by a single punching operation.

It is believed that the operation and use of the invention will be clear from the foregoing description, and it will not be again repeated. It will be understood, however, that various changes in the details, proportions and arrangements of parts which have been herein described and illustrated in order to explain the nature of the invention, may be made by those skilled in the art within the principle and scope of the invention as expressed in the appended claims.

I claim as my invention:

1. A holder formed of a plurality of flat plates abutting face to face sequentially and having a recess opening therein from an interior zone of the outside face of one of said plates at the end of a sequence and extending in a direction normal to said outside face into at least the third plate of said sequence, the portion of said recess in one of the interior plates of said sequence, and through which said recess extends from face to face, having an aperture therein from face to face, at one side of and intersecting the recess in that plate, and spaced by unapertured portions from the edges of that plate, a key confined in said aperture by the plates abutting the faces of said aperture and slidable therein into and out of a position partially across said recess, and a spring disposed between an edge of said aperture and an edge of said key for yieldingly and continuously urging said key into its said position, whereby when the shank of an element with a notch in its side is inserted into said recess with said notch alined with said aperture, said key may be projected into said notch to latch said element within said recess.

2. A holder formed of a plurality of flat plates abutting face to face sequentially and having a recess opening therein from an interior zone of the outside face of one of said plates at the end of a sequence and extending in a direction normal to said outside face into at least the third plate of said sequence, the portion of said recess in one of the interior plates of said sequence, and through which said recess extends from face to face, having an aperture therein from face to face, at one side of and intersecting the recess in that plate, and spaced by unapertured portions from the edges of that plate, a key confined in said aperture by the plates abutting the faces of said aperture and slidable therein into and out of a position partially across said recess, a spring disposed between an edge of said aperture and an edge of said key for yieldingly and continuously urging said key into its said position, and an element having a shank of a size to slide endwise along and rotate in said recess and having in its side a notch of a width into which said key may enter and which notch is alined with said aperture when said shank is fully within said recess, whereby when said shank is inserted endwise into said recess until the notch is alined with the apertures, said key may be projected into said notch to latch said element within the recess, said element also having a non-circular portion outside of said recess to receive a tool by which said element may be rotated and moved endwise in said recess.

3. A holder formed of a plurality of flat plates abutting face to face sequentially and having a recess opening therein from an interior zone of the outside face of one of said plates at the end of a sequence and extending in a direction normal to said outside face into at least the third plate of said sequence, the portion of said recess in one of the interior plates of said sequence, and through which said recess extends from face to face, having an aperture therein from face to face, at one side of and intersecting the recess in that plate, and spaced by unapertured portions from the edges of that plate, a key confined in said aperture by the plates abutting the faces of said aperture and slidable therein into and out of a position partially across said recess, and a spring disposed between an edge of said aperture and an edge of said key for yieldingly and continuously urging said key into its said position, said key having a thickness slightly less than the thickness of the apertured plate and being guided by opposite side edges of the aperture toward and from said recess, whereby when the shank of an element with a notch in its side is inserted into said recess with said notch alined with said aperture, said key may be projected into said notch to latch said element within said recess.

4. A holder formed of a plurality of flat plates abutting face to face sequentially and having a recess opening therein from an interior zone of the outside face of one of said plates at the end of a sequence and extending in a direction normal to said outside face into at least the third plate of said sequence, the portion of said recess in one of the interior plates of said sequence, and through which said recess extends from face to face, having an aperture therein from face to face at one side of and intersecting the recess in that plate, and spaced by unapertured portions from the edges of that plate, a key confined in said aperture by the plates abutting the faces of said aperture and slidable therein into and out of a position partially across said recess, a spring disposed between an edge of said aperture and an edge of said key for yieldingly and continuously urging said key into its said position, and an element having a shank of a size to slide endwise along and rotate in said recess and having in its side a notch of a width into which said key may enter and which notch is alined with said aperture when said shank is fully within said recess, whereby when said shank is inserted endwise into said recess until the notch is alined with the apertures, said key may be projected into said notch to latch said element within the recess, said element also having a non-circular portion outside of said recess to receive a tool by which said element may be rotated and moved endwise in said recess.

5. A holder formed of a plurality of flat plates abutting face to face sequentially and having a recess opening therein from an interior zone of the outside face of one of said plates at the end of a sequence and extending in a direction normal to said outside face into at least the third plate of said sequence, the portion of said recess in one of the interior plates of said sequence, and

through which said recess extends from face to face, having an aperture therein from face to face, at one side of and intersecting the recess in that plate, and spaced by unapertured portions from the edges of that plate, a key confined in said aperture by the plates abutting the faces of said aperture and slideable therein into and out of a position partially across said recess, a spring disposed between an edge of said aperture and an edge of said key for yieldingly and continuously urging said key into its said position, and an element having a shank of a size to slide endwise along and rotate in said recess and having in its side a notch of a width into which said key may enter and which notch is aligned with said aperture when said shank is fully within said recess, whereby when said shank is inserted endwise into said recess until the notch is aligned with the apertures, said key may be projected into said notch to latch said element within the recess, the end of said element first to enter said recess being chamfered along one edge, the side wall of said notch first to enter said recess being disposed in a plane approximately normal to the longitudinal axis of the recess, and said key having its face along the edge which engages with said side wall of said notch disposed parallel to that side wall.

6. A holder formed of a plurality of flat plates abutting face to face sequentially and having a cylindrical recess opening therein from an interior zone of the outside face of one of said plates at the end of a sequence and extending in a direction normal to said outside face into at least the third plate of said sequence, the portion of said recess in one of the interior plates of said sequence, and through which said recess extends from face to face, having an aperture therein from face to face, at one side of and intersecting the recess in that plate, and spaced by unapertured portions from the edges of that plate, a key confined in said aperture by the plates abutting the faces of said aperture and slideable therein into and out of a position partially across said recess, a spring disposed in said aperture and yieldingly urging said key into its said position, a punch element having a cylindrical shank approximately fitting said recess and slideable endwise and rotatable in said recess, said shank having a transverse kerf in a side wall thereof which is aligned with said aperture when said shank is substantially at its limit of movement into said recess and of a width to receive the adjacent edge of said key, a stripper disposed parallel to but spaced from the said one plate at the end of a sequence, said stripper being formed of two members abutting face to face and removably coupled together, studs carried by and extending from that one of said members which is nearest said holder and having a limited lost motion connection to said holder, whereby said stripper may have limited movement toward and from said holder, and means yieldingly urging said stripper in a direction away from said holder, said member carrying said studs having a hole therethrough from face to face in approximate alignment with said tool shank to enable a wrench to be inserted therethrough and engaged with said shank to rotate the latter and also move it endwise in said recess for engaging it in and disengaging it from said holder, the other of said members of said stripper having a passage therethrough aligned with the free end of said punch element and in which it reciprocates.

7. A punch device comprising a holder having

a recess opening into the same from one face thereof, a punch having a shank removably received in said recess, means carried by the holder for releasably clamping said punch in said recess, a stripper formed of a pair of members abutting face to face and removably coupled together, said stripper being disposed in face to face relation to but spaced from that face of said holder into which said shank extends, studs carried by that member of said stripper facing said holder and having a lost motion connection to said holder by which said stripper may have limited movement toward and from said holder, spring means acting between said holder and stripper for urging the latter in a direction away from said holder, said stripper member having said studs also having apertures aligned with said punch but substantially larger than the punch through which a tool may be inserted in a direction along said punch to grip the punch and turn it and move it endwise, the other member of said stripper having a passage therethrough slidably fitting the free end of said punch and into which the free end of said punch is withdrawn when said stripper is moved farthest from said holder.

8. A punch mounting comprising a holder having a recess opening therein from a face thereof, a punch having a shank slideable endwise and rotatable in said recess with the punch projecting from a face of the holder, a member disposed in spaced relation to said one face of said holder and carrying studs having limited endwise movement in said holder in a direction to guide said member toward and from said holder in the direction in which said punch extends, and also having a hole through which said punch extends, said punch having on its projecting portion, but between said member and said holder, a non-circular, shouldered portion by which the punch may be engaged and rotated and moved endwise in said recess, and said hole being of a size considerably larger than the shank of said punch to enable application of a tool to said punch at said shouldered portion and rotary and endwise movement given to the latter, springs yieldingly urging said member in a direction away from said holder, a second member in the form of a plate disposed flat against that face of said member farthest from said holder and having a passage therefrom aligned with and fitting the free end of said punch for slidably guiding said punch, and into which the free end of said punch may be received when said members are farthest from said holder, and means for removably coupling said members together face to face.

9. A punch mounting comprising a holder having a recess opening therein from a face thereof, a punch having a shank slideable endwise and rotatable in said recess with the punch projecting from a face of the holder, a member disposed in spaced relation to said one face of said holder and carrying studs having limited endwise movement in said holder in a direction to guide said member toward and from said holder in the direction in which said punch extends, and also having a hole through which said punch extends, said punch having on its projecting portion, but between said member and holder, a noncircular, shouldered portion by which the punch may be engaged and rotated and moved endwise in said recess, and said hole being of a size considerably larger than the shank of said punch to enable application of a tool to said punch at said shouldered portion and rotary and endwise movement given to the latter,

springs yieldingly urging said member in a direction away from said holder, a second member in the form of a plate disposed flat against that face of said member farthest from said holder and having a passage therethrough alined with and fitting the free end of said punch for slidingly guiding said punch, and into which the free end of said punch may be received when said members are farthest from said holder, a post carried by said second member and projecting toward said holder, said first mentioned member having a passage therethrough slidingly receiving said post, said post having a cylindrical free end with a transverse kerf in one side thereof, an element rotatably fitting the free end of said post and having a key therein yieldingly urged against the periphery of said post and into said kerf, said key being movable radially toward and from the longitudinal axis of said post, whereby upon relative rotary movement of said stud and element, the cylindrical portion of said post adjoining an end of said kerf will cam said key in a direction and for a distance sufficient to remove it from said kerf and enable endwise movement of said stud relatively to said element, the free end of said post being chamfered along its end edge at one side thereof to act as a cam for camming aside said key when said post is received in said element.

10. A coupling comprising a plurality of flat plates disposed to abut face to face sequentially and coupled together and having a recess opening therein from an interior zone of the outside face of one of said plates at the end of a sequence and extending in a direction normal to said outside face into at least the third plate of said sequence from said one plate, the second plate of said sequence from said one plate having therein an aperture entirely from face to face thereof, opening into said recess and encircled by unapertured portions so as to form with the plates abut-

ting its faces an entirely closed cavity opening solely into said recess, a flat key confined in said aperture by the plates abutting the faces of said apertured plate, having a thickness slightly less than the depth of said aperture from face to face, and movable in said aperture into and out of a position partially across said recess, a spring in said aperture urging said key into said position, the edge portion of said key which is projected partially across said recess being approximately flat and in a plane normal to the longitudinal axis of the recess on its face which is farthest from the outer end of said recess, whereby when the shank of an element with a notch in its side is received into said recess with the notch alined with said aperture, said key may be projected into said notch to latch said element within said recess.

11. A punch having a cylindrical mounting shank and a transverse, straight-sided kerf entirely across one side thereof and a second transverse, straight-sided kerf along another side of said shank at approximately a right angle to and intersecting with the first kerf and in the same peripheral zone.

12. A coupling comprising a holder having therein a recess opening therein from a face thereof, and a cavity intersecting said recess somewhat, an L-shaped flat key in said cavity and slideable therein into and out of a position partly across said recess, with the open side of the L towards said recess, an element having a cylindrical end rotatable and end-wise movable in said recess, said element having in the same circumferential zone a pair of transverse kerfs across the sides of said cylindrical end in alinement with said key when said end is within said recess and intersecting one another at approximately a right angle, said kerfs having widths which will receive an edge of said key when aligned therewith.
